(57) **CLAIM**

The ornamental design for a chucking flange for grinder disk, as shown and described.

DESCRIPTION

FIG. 1 is a top plan view of a chucking flange for grinder disk showing our new design;

FIG. 2 is a front elevational view thereof;

FIG. 3 is a right side elevational view thereof;

FIG. 4 is a bottom plan view thereof;

FIG. 5 is a cross-sectional view along line 5—5 in FIG. 1; and,

FIG. 6 is a perspective view thereof.

A rear elevational view is identical to the front elevational view.

A left side elevational view is identical to the right side elevational view.
